Shintaro Kako,

BY G. H. Strong

ATTORNEY

UNITED STATES PATENT OFFICE.

SHINTARO KAKO, OF SAN FRANCISCO, CALIFORNIA.

FLAT-IRON.

1,143,050.

Specification of Letters Patent. Patented June 15, 1915.

Application filed April 26, 1915. Serial No. 23,804.

To all whom it may concern:

Be it known that I, SHINTARO KAKO, a subject of the Emperor of Japan, residing in the city and county of San Francisco and State of California, have invented new and useful Improvements in Flat-Irons, of which the following is a specification.

This invention relates to flat irons, and particularly to an electrically heated iron provided with means for generating steam and properly applying the same to the garment or other article being pressed.

One of the objects of the invention is to provide an iron of the character described which is simple, substantial and compact and is so arranged that the steam generating and heating elements are all housed compactly within the iron structure.

Further objects will hereinafter appear. The invention consists of the parts and the construction and combination of parts as hereinafter more fully described and claimed, having reference to the accompanying drawings, in which—

Figure 1 is a central vertical section through the iron. Fig. 2 is a plan view of the bottom or facing plate of the iron.

More particularly described, A indicates the main body of the iron which is cored out to form a chamber 2 in which is suitably mounted a plurality of heating elements 3 which are connected with a suitable source of electric current supplied through means of a suitable form of plug connection, such as indicated at 4. The heating coils may be constructed and mounted in any suitable manner and insulated with relation to the iron proper.

Secured to the iron, by screws 5 or other means, is a housing 6 in which is formed a central steam generating chamber 7. Mounted on the housing 6 and suitably secured to same, as at 8, is a needle valve 9 to which water may be delivered through a flexible hose connection 10 or the like. Mounted on the lower end of the needle valve and projecting into chamber 7 is a nozzle 11, in the lower end of which is formed a plurality of radially disposed spray openings 12. Secured to the bottom of the main body section A of the iron, by means of screws 13, is a facing plate 14, and formed on the inner side of said plate is a longitudinally disposed groove 15 from which radiate a plurality of transversely disposed grooves 16. Connecting the main groove 15 with cham-

ber 7 is a steam conducting pipe 17, and formed in the face plate 14, in alinement with the grooves 16, are perforations 18.

In operation, when pressing garments or the like where a certain amount of moisture is needed, it is only necessary to slightly open the needle valve 9. Water is thus admitted to nozzle 11 and discharges therethrough in the form of a spray into chamber 7 where it is immediately generated into steam which is permitted to escape through pipe 17 into the grooves 15 and 16 formed in the facing plate 14. It is here permitted to escape through perforations 18. The steam is thus evenly and properly applied to the garment or other article to be pressed; the amount of steam applied being regulated by the needle valve 9.

The provision of the electrically operated heating elements not only transmits the desired temperature to the face plate 14, but also supplies sufficient heat to chamber 7 to generate the required or desired amount of steam. The iron is otherwise simple and compact in construction and is easily handled and adjusted when in operation as a slight turn of the needle valve in one direction or the other will vary the amount of steam generated.

A packing and insulating plate 19 is preferably interposed between the main body of the iron and the housing 6 to form the proper protection for the heating elements.

The materials and finish of the several parts of the iron are such as the experience and judgment of the manufacturer may dictate.

I wish it understood that various changes in form, proportions and details of construction may be resorted to within the scope of the appended claims and that I do not wish to limit myself to the specific design and construction here shown.

Having thus described my invention, what I claim and desire to secure by Letters Patent is—

1. In a flat-iron of the character described, the combination with the main body section having an electrically operated heating element mounted interiorly thereof, of a housing secured to the body section, said housing having a steam generating chamber formed therein, a facing plate secured to the body section, said facing plate having a longitudinal and a plurality of connected transverse steam discharging passages formed on

its inner side and a plurality of perforations formed in its face communicating with the transverse grooves, means for admitting water to the steam generating chamber, and means for conveying the steam to the longitudinal and connected transverse steam discharging passages in the face plate.

2. In a flat-iron of the character described, the combination with the main body section 10 having an electrically operated heating element mounted interiorly thereof, of a housing secured to the body section, said housing having a steam generating chamber formed therein, a facing plate secured to the 15 body section, said facing plate having a longitudinal and a plurality of connected transverse steam discharging passages formed on

its inner side and a plurality of perforations formed on its face communicating with the transverse grooves, a needle valve mounted 20 on the housing, a spray nozzle connected with the needle valve and projecting into the steam generating chamber, and a pipe forming communication between the steam chamber and the longitudinal and connected 25 transverse steam discharging passages.

In testimony whereof I have hereunto set my hand in the presence of two subscribing witnesses.

SHINTARO KAKO.
